Primary Examiner—Robin Webster*Assistant Examiner*—Karen E. Patterson(74) Attorney, Agent, or Firm—Wolf Block Schorr & Solis-Cohen LLP(57) CLAIM

We claim the ornamental design for food casing, as shown and described.

DESCRIPTION

The sole FIGURE illustrates a front view of the food casing of the present invention, the rear view thereof being identical to the front view.

The right side view, left side view, top view and bottom view are flat and devoid of surface ornamentation.
